(57) **CLAIM**

The ornamental design for a coffee press, as shown and described.

DESCRIPTION

FIG. 1 is a perspective view of a first embodiment of the coffee press showing my design thereof;

FIG. 2 is a front view thereof;

FIG. 3 is a back view thereof;

FIG. 4 is a right side view thereof;

FIG. 5 is a left side view thereof;

FIG. 6 is a top view thereof;

FIG. 7 is a bottom view thereof;

FIG. 8 is a cross-sectional view thereof;

FIG. 9 is a perspective view of a second embodiment of the coffee press showing my design thereof;

FIG. 10 is a front view thereof;

FIG. 11 is a back view thereof;

FIG. 12 is a right side view thereof;

FIG. 13 is a left side view thereof;

FIG. 14 is a top view thereof;

FIG. 15 is a bottom view thereof;

FIG. 16 is a cross-sectional view thereof;

FIG. 17 is a perspective view of a third embodiment of the coffee press showing my design thereof;

FIG. 18 is a front view thereof;

FIG. 19 is a back view thereof;

FIG. 20 is a right side view thereof;

FIG. 21 is a left side view thereof;

FIG. 22 is a top view thereof;

FIG. 23 is a bottom view thereof;

FIG. 24 is a cross-sectional view thereof;

FIG. 25 is a perspective view of a fourth embodiment of the coffee press showing my design thereof;

FIG. 26 is a front view thereof;

FIG. 27 is a back view thereof;

FIG. 28 is a right side view thereof;

FIG. 29 is a left side view thereof;

FIG. 30 is a top view thereof;

FIG. 31 is a bottom view thereof;

FIG. 32 is a cross-sectional view thereof;

FIG. 33 is a perspective view of a fifth embodiment of the coffee press showing my design thereof;

FIG. 34 is a front view thereof;

FIG. 35 is a back view thereof;

FIG. 36 is a right side view thereof;

FIG. 37 is a left side view thereof;

FIG. 38 is a top view thereof;

FIG. 39 is a bottom view thereof; and,

FIG. 40 is a cross-sectional view thereof.
